UNITED STATES PATENT OFFICE.

GEORGE A. CONNOR, OF NORWOOD, OHIO, ASSIGNOR TO NORWOOD NOVELTY CO., OF NORWOOD, OHIO, A CORPORATION OF OHIO.

DESIGN FOR A TOY VEHICLE.

54,380.

Specification for Design.

Patented Feb. 10, 1920.

Application filed May 20, 1919. Serial No. 298,564. Term of patent 14 years.

To all whom it may concern:

Be it known that I, GEORGE A. CONNOR, a citizen of the United States, residing at Norwood, in the county of Hamilton and State of Ohio, have invented a new, original, and ornamental Design for a Toy Vehicle, of which the following is a specification, reference being had to the accompanying drawing, forming a part thereof.

The figure is a perspective view of a toy showing my new design.

I claim:

The ornamental design for a toy vehicle as shown.

GEORGE A. CONNOR.
